GARMENT HANGER

Filed March 28, 1929

Inventor

PHILLIP O. SHRACK

284 Watson E. Coleman.

attorney

UNITED STATES PATENT OFFICE

PHILLIP OVID SHRACK, OF DUBUQUE, IOWA

GARMENT HANGER

Application filed March 28, 1929. Serial No. 350,727.

This invention relates to a garment hanger and it is an object of the invention to provide a device of this kind constructed in a manner whereby it can be conveniently applied to small neck dresses and other garments.

Another object of the invention is to provide a device of this kind comprising two sections, one of which having slideable connection with the other, and wherein the sections are provided with means for holding the arms rigidly in extended or working position yet permitting the hanger to be easily folded when desired.

15 The invention consists in the details of construction and in the combination and arrangement of the several parts of my improved garment hanger whereby certain important advantages are attained and the device rendered simpler, less expensive and otherwise more convenient and advantageous for use, as will be hereinafter more fully set forth.

20

The novel features of my invention will hereinafter be definitely claimed.

In order that my invention may be the better understood, I will now proceed to describe the same with reference to the accompanying drawing, wherein:—

30 Figure 1 is an elevational view of a garment hanger constructed in accordance with an embodiment of my invention with the arms extended;

Figure 2 is an elevational view of the device as herein disclosed folded;

Figure 3 is a detailed sectional view illustrating a means for holding an arm extended.

As herein embodied, my improved hanger comprises two sections A and B. The section A comprises an elongated arm 1 preferably formed of wire of requisite gauge and having its outer end portion returned, as at 2, so that said arm can be effectively engaged with a garment without injury thereto. The opposite end portion of the arm 1 is continued to provide a depending and substantially semi-circular loop 3 disposed inwardly of the arm 1. The inner portion of the loop 3 is free from the arm 1 and is continued by a second arm 4 of desired length and

having its outer end portion free to provide an inwardly facing hook member 5 whereby the device in its entirety can be suspended from a desired support.

The section B comprises an arm 1' having its outer end portion returned, as at 2', and with its opposite or inner end portion formed with a loop 3' substantially similar to the loop 3 hereinbefore referred to. The inner portion of the loop 3' is continued by an arm 6 which is free of the arm 1' and extends a desired distance thereabove. The free end portion of the arm 6 is rigidly connected, as at 7, to the arm 4 at a desired point between the inner portion of the arm 1 and the hook member 5. This connection 7 is preferably provided by coiling or twisting together the free end portion of the arm 6 and the associated portion of the arm 4.

The inner portion of the arm 1 is freely directed through the loop 3' while the arm 1' is freely directed through the loop 3 and when the arms are in their raised or extended position, the inner portion of the arm 1 has close contact with the inner portion of the arm 1' and the inner portion of the arm 1' has contact with the inner portion of the arm 1.

The outer portion of each of the loops 3 or 3' at its junction with the arm 1 or 1' is offset, as at 8, to provide a pocket or recess 80 to engage from below the arm 1 or 1' whereby said arms 1 and 1' are effectively supported in their raised or extended position.

When it is desired to fold the hanger, the arms 1 and 1' are freed from the pockets or recesses 8 and swung inwardly one toward the other as illustrated in Figure 2, the resultant contact of the arms 1 and 1' and the loops 3 and 3' effectively locking the hanger in such folded relation.

From the foregoing description it is thought to be obvious that a garment hanger constructed in accordance with my invention is particularly well adapted for use by reason of the convenience and facility with which it may be assembled and used, and it will also be obvious that my invention is susceptible of some change and modification without departing from the principles and spirit thereof and for this reason I do not wish to be un-

derstood as limiting myself to the precise arrangement and formation of the several parts herein shown in carrying out my invention in practice except as hereinafter claimed.

5 I claim:—

1. A foldable garment hanger made of wire and comprising two sections, each of said sections having an elongated arm, the inner end of each of the arms being returned 10 to provide a substantially semi-circular depending loop terminating in an upstanding arm, the inner portion of the first named arm extending through the loop of the similar arm of the second section and having contact 15 with the first named arm of the second section when both of said arms are extended, the extended arm of the loop of one section having its free end portion connected to the extended arm of the loop of the second section. 20
2. A foldable garment hanger made of wire and comprising two sections, each of said sections having an elongated arm, the inner end of each of the arms being returned 25 to provide a substantially semi-circular depending loop terminating in an upstanding arm, the inner portion of the first named arm extending through the loop of the similar arm of the second section and having contact 30 with the first named arm of the second section when both of said arms are extended, the extended arm of the loop of one section having its free end portion connected to the extended arm of the loop of the second section. 35
3. A foldable garment hanger made of wire and comprising two sections, each of said sections having an elongated arm, the inner end of each of the arms being returned 40 to provide a substantially semi-circular depending loop terminating in an upstanding arm, the inner portion of the first named arm extending through the loop of the similar arm of the second section and having contact with the first named arm of the second section when the first named arms of both of the sections are extended.

In testimony whereof I hereunto affix my signature.

PHILLIP OVID SHRACK.
